SOFT HELMET FOR CARRYING SOUND ATTENUATING EARMUFFS

Jackson A. Aileo, Carbondale, Pa., assignor to Leonard P. Frieder, Great Neck, N.Y.

Filed Feb. 11, 1959, Ser. No. 792,625

3 Claims. (Cl. 2-3)

This invention relates to ear coverings and ear pieces of the sound attenuating type, with or without ear phones and especially to apparatus for supporting such an ear piece in an operating position covering the wearer's ear.

It is desirable to protect the ears of persons who are required to work in the vicinity of machines producing intense noises. This problem is particularly acute among personnel required to work in the vicinity of jet aircraft.

In order to provide such protection, it has been proposed to provide sound attenuating housing structures which are typically rigid shells, and to mount those structures on a helmet, a headband, or the like, so that they may be held fixed in place over the wearer's ears.

There is shown and described in the copending application for United States Letters Patent of Walter S. Finken and Jackson A. Aileo, Serial No. 571,451, filed March 14, 1956, now Patent No. 2,871,484, granted February 3, 1959, a close-fitting helmet which is adapted to support earphones or the like in position over the wearer's ears.

One of the problems with any device for supporting ear pieces resulting from the necessity of an angular adjustment. The ear pieces are preferably made generally ellipsoidal, so as to conform to the shape of the human ear. The relationship of the ear position to the skull contour varies considerably from one person to another, so that an angular setting of the ear pieces in a helmet which is suitable and comfortable for one person may not be suitable and comfortable for another.

An object of the present invention is to provide an improved means for mounting an ear piece in a position where it effectively covers the ear of a wearer and prevents impingement of external sounds on the ear.

Another object is to provide an improved means for mounting an ear piece on a helmet of the type described in the Finken et al. application Serial No. 571,451, mentioned above, including improved means for angularly adjusting the position of the ear piece relative to the helmet.

A further object is to provide improved means for angularly adjusting the position of any ellipsoidal ear piece relative to its supporting structure.

The foregoing objects are attained by providing in a helmet or head covering of flexible material, an aperture whose contour and peripheral dimension are substantially the same as the contour and peripheral dimension of the ellipsoidal housing of the ear piece. Suitable means are provided on the housing for engaging the edge of the panel so as to hold the housing fixed in position on the panel. Since the aperture in the panel is made elliptical, it fits the ellipsoidal housing in a particular preferred angular position thereof, and tends to oppose movement of the ellipsoidal housing from that particular angular position. The material of the side panel is sufficiently flexible, however, so that the housing may be moved, with only a slight application of force, away from its preferred angular position. In the new angular position, some part of the panel will be bias stressed because of the lack of alignment between the housing and the aperture. The bias stressed part of the panel will closely conform to and frictionally engage the periphery of the housing, and will hold the housing in its new angular position.

In certain species of the invention disclosed herein, the edge of the aperture in the panel is covered by a tape which overlaps both the inner and outer margins of the

2

panel. The ear piece housing is provided with a pair of spaced peripheral flanges which define a channel between them for receiving the taped edge of the panel opening.

In another species of the invention described herein, a similar taped edge is provided on the panel, and the attachment means on the housing comprises a number of spaced clamps which extend over and grip the panel material inside the taped edge.

In either of the species described above, a resilient wire may be sewn inside the tape.

Other objects and advantages of the invention will become apparent from a consideration of the appended specification and claims, taken together with the accompanying drawings.

15 In the drawings:

FIG. 1 is a side elevational view of a helmet with an ear piece constructed in accordance with the invention, mounted on the head of a person;

20 FIG. 2 is a fragmentary view on an enlarged scale, similar to FIG. 1, showing the ear piece and the adjacent portion of the side panel of the helmet;

FIG. 3 is a view similar to FIG. 2, showing the side panel of the helmet with the aperture therein, and the ear piece removed;

25 FIG. 4 is a cross-sectional view taken on the line IV-IV of FIG. 2;

FIG. 5 is a front view of a helmet embodying a modification of the invention and mounted on the head of a person;

30 FIG. 6 is a view similar to FIG. 2, but illustrating the modification shown in FIG. 5;

FIG. 7 is a cross-sectional view taken on the line VII-VII of FIG. 6;

35 FIG. 8 is a view similar to FIG. 3, but showing the modification of FIGS. 5 to 7, and partly broken away to reveal the wire construction;

FIG. 9 is a sectional view similar to FIGS. 4 and 7, illustrating a modification; and

40 FIG. 10 is a view similar to FIG. 1, illustrating the modification of FIG. 9.

FIGURES 1 to 4

There is shown in FIG. 1 a helmet generally indicated by the reference numeral 1, which may be constructed as shown and described in detail in the copending Finken et al. application Serial No. 571,451. This helmet comprises two central zones, one of which is seen at 2 in the drawing, and which extend over the wearer's head from the forehead to the nape of the neck. A side panel 3 is attached along the lateral portion of the zone 2. A tape 4 extends around the periphery of the helmet, and a strip 5 covers the wearer's forehead below the tape 4.

50 The side panel 3 is provided with an opening 3a, whose unstressed contour is generally elliptical, as seen at 3a in FIG. 3. This opening is positioned in the side panel so as to be aligned with an ear of the wearer when the helmet is in place on the head. A tape 6 is sewn over the edge of the opening 3a by means of a row of stitching 7. As shown in FIG. 4, the tape covers both the inner and outer margins of the panel around the opening 3a.

55 Inside the opening 3a there is inserted an ear piece 8, comprising a rigid casing of generally ellipsoidal contour, preferably of molded plastic material, and best seen in FIG. 2. As shown in detail in FIG. 4, the ear piece 8 comprises an inner shell 8a and a conforming outer shell 8b bonded together. The inner shell 8a is provided with a peripheral flange 8d and the outer shell 8b has a similar peripheral flange 8e. The flanges between them define a channel indicated by the reference numeral 9 for receiving the taped edge of the panel 3 around the opening 3a.

60 The contour and peripheral dimension of the aperture 3a should be substantially the same as the contour and

peripheral dimension of the channel 9 around the ear piece 8. If those contours and dimensions are made substantially the same, then the tapered edge of the opening 3a may be readily slipped into the channel 9 so as to support the ear piece 8 in alignment with the wearer's ear. The edge of the panel 3 may be made to fit snugly against the ear piece throughout the periphery of the ear piece and of the aperture 3a. If these contour and dimensional relationships are maintained, the snug frictional fit between the tape 7 and the sides of the channel 9 will maintain the ear piece fixed in any angular position in which it is set. Furthermore, the ear piece 8 may be rotated from the position shown in full lines in FIG. 2 to any other angular position, for example, the position shown by the dot-dash line in FIG. 2. This rotation is accomplished simply by holding the panel 3 and rotating the ear piece 8. The frictional engagement between the panel 3 and the ear piece 8 will allow such rotation by the application of a moderate force.

When the panel 3 and the ear piece 8 are relatively rotated away from their preferred angular positions wherein their elliptical contours are aligned, some part of the panel is bias stressed, i.e., stressed unevenly and along lines which cross both the weft and woof of the weave. The biased stressed part of the panel at the margin of the opening 3a closely conforms to and frictionally engages the periphery of the housing and holds the housing in its new angular position. Consequently, the ear piece 8 may be set and will stay in any desired angular position with respect to the panel 3.

Instead of having the inner shell 8a and the outer shell 8b closely conforming throughout their central portions, as shown in the drawing, they may be provided with a dead air space between the two shells. Alternatively, that space may be filled with some sound deadening means, such as a chemical foam of the vinyl or polyurethane type. As another alternative, it may be desirable to fill that space with some material having a large inertial mass, such as a lead compound or lead film.

The helmet 1 is provided with a chin strap 11, for holding the side panels 3 tightly against the wearer's head. A backstrap 12 is also provided which extends from a point under the tape 4 at the front of the helmet over the ear piece 8 and the panel 3. A size take-up mechanism is provided in the strap 12. This strap further assists in holding the panel 3 and the ear piece 8 in proper alignment with the wearer's ear.

FIGURES 5 to 8

These figures illustrate a slightly modified form of helmet and a modified form of attachment of an ear piece to the helmet. A helmet 13 of FIG. 5 comprises two central zones 14 and two side panels 15. Two ear pieces 16 are mounted on the side panels 15. A chin strap 17 is provided for holding the side panels 15 tightly in engagement with the wearer's head.

Each of the side panels 15 is provided with a circular opening 15a, best seen in FIG. 8. The marginal portions of the openings 15a are covered by a tape 18 held in place by a row of stitching 19. Inside the tape is inserted a resilient circular wire 20 which tends to hold the periphery of the opening 15a in a circular contour, even though it is cut with an elliptical contour as in FIG. 3. The diameter of the circle formed by the wire 20 is made slightly larger than the diameter of the opening 15a when the panel 15 is unstressed. By virtue of that arrangement, the wire 20 stretches the tape 18 and the adjacent margin of the panel 15 and thereby forms a sort of flange which projects out of the plane of the panel 15. See FIGS. 7 and 8.

The wire 20 and the material of the panel 15a may be bent and stressed so that they fit closely the periphery of an elliptical ear piece housing 21. On the periphery of the housing 21 there is provided a plurality of clamps 22. Each clamp comprises a generally L-shaped clamp bar

23, having one long leg and one short leg, and a screw 24 extending through an aperture in the long leg of the bar 23 and threaded into the housing 21. The short leg of the clamp 23 extends over the flange formed by the tape 18 and the wire 20 therein, and holds the tape 18 tightly in engagement with the periphery of the ear piece 21.

The angular position of the ear piece 21 relative to the panel 15 may be changed by loosening the screws 24 so that the tape 18 enclosing the wire 20 may slip freely under the clamp bars 23. After a suitable angular adjustment is attained, the screws 24 may again be tightened. The ear piece 21 may be provided with a sound attenuating pad 25 or other similar mechanism for resiliently and snugly engaging the side of the wearer's head around the entire periphery of the ear.

The structures disclosed herein are extremely light in weight, yet they provide fixed angular adjustment of the ear pieces, which nevertheless may be modified at will by the wearer.

FIGURES 9 and 10

These figures illustrate a modification of the invention which is generally similar to that shown in FIGS. 1 to 4 but in which the back strap 12 is eliminated. In FIG. 9, the ear piece 8 of FIG. 1 is replaced by an ear piece generally indicated at 26 and comprising an ellipsoidal shell 27 having a flange 27a on its head-engaging side. As in FIG. 7, a sound attenuating pad 28 is provided for resiliently and snugly engaging the wearer's head around the entire periphery of the ear. The pad 28 is fixed to the flange 27a by any suitable means.

On the outside of the shell 27, spaced outwardly from the flange 27a, there are provided a pair of spaced parallel flanges 27b defining between them a channel 27c for receiving the edge of a panel 29 which corresponds generally to the panel 3 of FIG. 1. The panel 29 is provided with a central aperture of elliptical contour. The edge of the aperture is covered by a tape 30, corresponding to the tape 6 of FIGS. 1 to 4. The panel 29 is constructed somewhat differently than the panel 3 of FIG. 1. When the helmet 31, of which the panel 29 is a part, is mounted on the wearer's head, the peripheral edges of the panel are held in close engagement with the head by the other parts of the helmet structure. The central portion of the panel 29 is held away from the wearer's head by the flanges 27b on the shell 27. The panel 29 is therefore stretched outwardly at its central portion. The panel 29 and the connection between the panel and the shell 27 perform the function of the back strap 12 of FIG. 1. That is to say, the panel 29 is effective to hold the cushion 28 in snug engagement with the wearer's head. The back strap 12 may be eliminated.

If desired, a wire such as the wire 20 of FIGS. 7 and 8 may be used inside the tape 30 of FIG. 9. Such a wire may also be used inside the tape 6 of FIG. 4.

While I have shown and described certain preferred embodiments of my invention, other modifications thereof will readily occur to those skilled in the art and I therefore intend my invention to be limited only by the appended claims.

I claim:

1. A helmet adapted to cover the head of the wearer comprising at least one side panel of flexible woven material adapted to engage the side of the wearer's head, said panel having an aperture of generally elliptical peripheral contour disposed adjacent the wearer's ear when the helmet is in place on the head, an ear piece having a rigid generally ellipsoidal casing adapted to cover the wearer's ear and provided at the side thereof toward the ear with an opening communicating with the ear, the exterior surface of said casing along a peripheral dimension thereof generally parallel to and adjacent the side of the wearer's head being of generally elliptical contour, said casing carrying exteriorly thereof spaced flanges integrally formed therewith and defining therebetween

and with said exterior surface of said casing along said peripheral dimension a channel extending about said casing generally parallel to and adjacent the side of the wearer's head, said channel receiving therein the edge portion of the panel adjacent and along said elliptical peripheral contour of said aperture of said panel, said peripheral dimension of said casing along said channel between said flanges being substantially equal to the peripheral dimension of said aperture of said panel, the portion of said panel along the periphery of said aperture being slidable in said channel relative to said casing to adjust the angular position of said casing with respect to said side panel, said material of said side panel being substantially inelastic but sufficiently flexible and capable of being bias stressed adjacent said aperture therein to permit said sliding movement of said portion of said panel in said channel between said flanges while providing snug engagement of said portion of said panel with said exterior surface of said casing so as to cooperate with said casing and said flanges to hold the casing in any adjusted angular position.

2. A helmet as defined in claim 1 which comprises a tape folded over the marginal portions of and upon both surfaces of said panel along the periphery of said aperture, and stitching fastening said tape to both surfaces of said panel, said taped marginal portions of said panel being received in said channel of said casing.

3. A helmet adapted to cover the head of the wearer comprising at least one side panel of flexible material adapted to engage the side of the wearer's head, said panel having an aperture of generally elliptical peripheral contour disposed adjacent the wearer's ear when the helmet is in place on the head, an ear piece having a rigid generally ellipsoidal casing adapted to cover the wearer's ear and provided at the side thereof toward the ear with an opening communicating with the ear, the exterior

surface of said casing along a peripheral dimension thereof generally parallel to and adjacent the side of the wearer's head being of generally elliptical contour, said casing carrying exteriorly thereof spaced flanges integrally formed therewith and defining therebetween and with said exterior surface of said casing along said peripheral dimension a channel extending about said casing generally parallel to and adjacent the side of the wearer's head, said channel receiving therein the edge portion of the panel adjacent and along said elliptical peripheral contour of said aperture of said panel, said peripheral dimension of said casing along said channel between said flanges being substantially equal to the peripheral dimension of said aperture of said panel, the portion of said panel along the periphery of said aperture being slidable in said channel relative to said casing to adjust the angular position of said casing with respect to said side panel, said material of said side panel being substantially inelastic but sufficiently flexible and capable of being stretched adjacent said aperture therein to permit said sliding movement of said portion of said panel in said channel between said flanges while providing snug engagement of said portion of said panel with said exterior surface of said casing so as to cooperate with said casing and said flanges to hold the casing in any adjusted angular position.
